UNITED STATES PATENT OFFICE

128,384

DESIGN FOR A COMBINED CONTROL AND DOOR TRIM UNIT FOR A REFRIGERATOR OR THE LIKE

Joseph N. Roth, Belding, Mich., assignor to Gibson Electric Refrigerator Corporation, a corporation of Michigan

Application February 24, 1941, Serial No. 99,188

Term of patent 14 years

To all whom it may concern:

Be it known that I, Joseph N. Roth, a citizen of the United States, residing at Belding, in the county of Ionia and State of Michigan, have invented a new, original, and ornamental Design for a Combined Control and Door Trim Unit for a Refrigerator or the like, of which the following is a specification, reference being had to the accompanying drawing, forming a part thereof, in which:

Figure 1 is a front elevational view of a com-

bined control and door trim unit, for a refrigerator or the like, showing my design; and Figure 2 is an enlarged top plan view of the control element, a fragmentary portion of the door trim element also being shown on an enlarged scale.

I claim:

The ornamental design for a combined control and door trim unit, for a refrigerator or the like, as shown and described.

JOSEPH N. ROTH.
